JOHN DITTRICK, OF PERTH, ONTARIO, CANADA.

HAMMOCK-SUPPORT.

1,320,381.

Specification of Letters Patent.

Patented Nov. 4, 1919.

Application filed October 8, 1917. Serial No. 195,419.

To all whom it may concern:

Be it known that I, JOHN DITTRICK, a subject of the King of Great Britain, and a resident of the town of Perth, in the Province of Ontario and the Dominion of Canada, have invented certain new and useful Improvements in Hammock-Supports, of which the following is a specification.

This invention relates to hammock supports and the objects of the invention are to render the support collapsible, so that it will occupy a minimum of space when folded up, thereby facilitating shipping or storing during winter months when hammocks are out of commission.

Further objects are to render the support of a portable nature so that the hammock may be readily placed in any position to suit the requirements of the user, to permit of the several parts of the support being quickly assembled to combine durability with lightness of construction, so that no inconvenience will be experienced during the moving of the support when the position of the hammock is being altered, and generally to adapt the several parts to better perform the functions required of them.

With the above and other objects in view, the invention consists essentially of the improved construction particularly described and set forth in the following specification and accompanying drawings forming part of the same.

In the drawings:

Figure 1 is a perspective view of a toy hammock support.

Fig. 2 is a perspective view part being broken away and in section of an embodiment of the invention as applied to hammocks in every day use.

Fig. 3 is a sectional detail of the device when folded.

Like characters of reference refer to like parts in the several figures.

Referring to the drawings, A represents the improved hammock support and B the hammock slung thereon. The support A comprises a base 10, which in that form of the invention illustrated in Fig. 1 consists of two portions 8 and 9 connected at their adjacent ends by the hinge 11, the base being substantially rectangular and provided with a central orifice 12 which gives lightness to the structure. At each end of the frame a projection 13 is formed provided with an outer beveled face 14, and to these projec-

tions the arms 15 are connected by the hinges 16.

It should be particularly noted that the hinges 16 are located adjacent to the lower ends of the arms 15, and that the lower projecting part of each arm is adapted when in an upright inclined position to engage the beveled face 14 of the projection 13 which acts as a stop member and limits the backward movement of the arms. Each arm 15 is provided with a bail 17 pivotally attached at one end thereto, the other end of the bail being adapted to engage with a pin or stop member 18 secured to the base 10 adjacent to the projection 13.

Toward the upper end of each arm 15, a hook 19 is secured from which the hammock is suspended. When the device is to be shipped, the hammock B is removed and rolled up into a small bundle, whereupon the bails 17 are disengaged from the pins 18 and the arms 15 rotated in a vertical plane into a horizontal position, whereupon the two portions 8 and 9 of the base 10 are folded one on top of the other, making a small compact bundle of the support.

In that form of the invention illustrated in Fig. 2, the support A consists of a pair of longitudinally extending members 20 held in spaced relation by the transversely extending members 21 and 22, secured to the bottom thereof. At the ends of the members 20 the arms 15^a are pivotally attached by the hinge pins 16^a, and the lower ends of the arms below the hinge pin are adapted, when the arms are elevated and angularly disposed, to engage with the transversely extending stop members 21 which limit the rotation of the arms.

The arms 15^a are locked in an angular position by the hinge member 23, which is provided with a knuckle joint, so that when the hinge is opened the arms will not yield or become liable to collapse when a force is exerted thereon. This hinge member 23 is pivoted at one end to the arm 15^a and at the other end to the transversely extending member 22.

To give the support A the desired stability, so that it will not rock laterally, I provide adjacent to each end a transversely extending bar 24, which is located below the members 20, and is secured in position by means of a bolt 25 which passes through the clamping plate 26 located above the said members. The arms 15^a are provided adj-

cent to their upper end with hooks 19^a from which the hammock B is designed to be slung.

In assembling this form of hammock support A, the arms 15^a are rotated into an upward angular position in which the lower end of each arm engages with the transversely extending members 22 and in this position the hinge member 23 will be 10 fully opened, so that the knuckle joint of the hinge member interlocks and thus prevents any liability of collapse of the hinge when the load comes upon the support. The transverse bars 24 are next located and secured in position by the clamping plate 26 and bolt 25. When the arms 15^a have been 15 so arranged, the hammock B is then slung in position.

In disassembling this form of support it is 20 only necessary to loosen the bolts 25 when the clamping plate can be rotated until it falls between the side members 20 whereupon the transverse bars 24 are free to be removed from and placed along side of the 25 members 20. The hinge members 23 are now pulled outwardly at the joint and the arms 15^a rotated in a vertical plane until they lie between the members 20, so making a compact bundle of the support ready for shipping.

From this description it will be seen that I have invented a hammock support of an extremely simple nature, light in construction yet durable and capable of being set up or knocked down in a few minutes, so simplifying shipping and storing.

The device may be used not only in the ordinary way to support a full sized hammock but also as a toy in miniature size to 40 support a doll's hammock or the like.

As many changes could be made in the

above construction and many apparently widely different embodiments of my invention, within the scope of the claim, constructed without departing from the spirit 45 or scope thereof, it is intended that all matter contained in the accompanying specification and drawings shall be interpreted as illustrative and not in a limiting sense.

What I claim as my invention is:

A device of the class described comprising two U-shaped members hinged together end to end with the legs of the U-shaped members abutting, the outer ends of the U-shaped members being beveled downwardly and inwardly, hammock supporting arms hinged to the U-shaped members at the base of the U, the hinge being on the face of the U-shaped members opposite the hinges securing the legs together, a portion of the 60 arms being below the hinges whereby they engage with the beveled edge of the U-shaped members so that their pivotal movement outwardly is limited but greater than a right angle and forms an obtuse angle with the 65 upper face of the U-shaped members, and locking members for securing the arms in operative position including pivoted bails 17 on the arms, and studs on the U-shaped members adapted to engage the ends of the bails, 70 the device when folded having the two U-shaped members bent back upon themselves, and the arms folded upon their adjacent U-shaped members, so that the U-shaped members when folded lie between the folded 75 arms.

In witness whereof I have hereunto set my hand in the presence of two witnesses.

JOHN DITTRICK.
